(57) **CLAIM**

I claim the ornamental design for a watch face, as shown and described.

DESCRIPTION

FIG. 1 is a perspective view of a watch face, showing my new design; and,

FIG. 2 is a front elevational view thereof.

The broken lines showing clock hands in FIG. 1 depict environmental matter and form no part of the claimed design.

1 Claim, 2 Drawing SheetsFIG. 1

FIG. 2
